INDICATING PLUG FUSE

Frank C. La Mar, New York, N. Y.

Application February 19, 1932, Serial No. 594,024

5 Claims. (Cl. 200—121)

This invention relates to electrical devices, particularly to thermal fuses for use in connection with electrical circuits, and more especially to what is known as a plug fuse, combined with 5 means for indicating the integrity of the fusible element.

It is quite universally known that it is necessary to protect electrical circuits by means of devices, such as thermal fuses, which melt or become disintegrated or destroyed when an excessive flow of current passes through the circuit of which the fuse forms a part. An especially well known form of thermal fuse is that known as "plug fuses". Ordinary plug fuses consist, generally, of an insulating body having two terminals on the outside thereof so constructed and arranged as to be readily brought in contact with the terminals of an electrical circuit, by way of what is known usually as a fuse block. These 20 fuses are so universally used, and are made by so many different manufacturers, and must all be usable in practically any of the well known forms of fuse block, that they have become, in truth, standard, so that they may well be referred to as, standard, fuse plugs. At any rate they are substantially standard as regards their general external dimensions.

Various forms of plug fuses have been made, especially for the purpose of enabling one to 30 rapidly discern whether or not the fusible or thermal element is intact. It is quite the universal impression that success has not been attained in regard to the feature of indicating the integrity of the fusible element.

35 A principal object of applicant's invention is to provide a device, which may well be called a combined fuse and fuse integrity indicating device. In providing such a device, applicant has had in mind that it preferably should be in external dimensions substantially the size of the 40 standard plug fuse, so that it may be used with a facility equal to that of a plug fuse in those situations where a plug fuse is now used.

A further object which applicant has in mind 45 in producing his combined fuse and fuse integrity indicator is that the cost must be reduced to a point where, if possible, it approximates the present cost of ordinary plug fuses. To this end, applicant has, as a further object of his 50 invention, the production of a device in two parts, separable one from the other, one part performing the functions now performed by the ordinary plug fuse, and the other part performing the indicating functions desired by applicant.

55 A further object of applicant's invention is to

produce a combined fuse and fuse integrity indicator which will be substantially the same external dimensions as a standard plug fuse.

Other objects and advantages will appear as the description of the particular physical embodiments selected to illustrate the invention progresses, and the novel features will be particularly pointed out in the appended claims.

In describing the invention in detail and the particular physical embodiments selected to illustrate the invention, reference will be had to the accompanying drawing and the several views thereon, in which like characters of reference designate like parts throughout the several views, and in which:

Figure 1 is a top plan view of a device embodying applicant's invention of a combined fuse and fuse integrity indicator; Fig. 2 is an elevational view of the device as shown by Fig. 1; Fig. 3 is a top plan view of applicant's device, as shown by Fig. 1, but with the separable indicating portion removed; Fig. 4 is a top plan view of the separable indicating portion of applicant's invention with the top cover removed; Fig. 5 is an enlarged elevational cross-sectional view of the device as shown by Fig. 2; Fig. 6 is an enlarged elevational cross-sectional view of the device as shown by Fig. 2, taken on a plane at a right angle to the plane upon which Fig. 5 is taken; Fig. 7 is an elevational view, partly in section, of a modified form of applicant's combined fuse and fuse integrity indicator; Fig. 8 is an elevational cross-sectional view of another modified form embodying applicant's invention of a combined fuse and fuse integrity indicator; Fig. 9 is a fragmentary 90 elevational view illustrating the parts of a portion of the device, as shown by Fig. 8, as viewed from either side thereof as shown in Fig. 8; Fig. 10 is an elevational cross-sectional view of another modified form of device embodying applicant's 95 invention; Fig. 11 is an elevational cross-sectional view of the device as shown by Fig. 10, but taken upon a plane at a right angle to the plane upon which the view, Fig. 10, is taken.

The parts corresponding to the parts of the 100 ordinary standard plug fuse are well illustrated by Figs. 2 and 5. Just as in the device illustrated in Figs. 2 and 5, the ordinary plug fuse includes a body of insulating material, generally hollow, 1; a threaded metallic shell or terminal 2 attached to the body; a metallic button or terminal 3; a metallic conductor 4 and a metallic conductor 5, one in electrical contact with the terminal 3, and the other in electrical contact with the threaded shell terminal 2, both of which at some portion 110

of their length are exposed as at 6 and 7 in the hollow interior of the plug; and a fusible or thermal element 8 connecting the members 4 and 5 at the points 6 and 7 respectively. All of the 5 parts hereinbefore described, arranged substantially as shown, are common and ordinarily found in the ordinary standard plug fuse. The ordinary standard plug fuse includes an enlarged portion 9 forming the manually manipulative portion 10 of the plug fuse, by which it is grasped when it is screwed into a fuse block for insertion in an electrical circuit.

Applicant's device contains not only all of the parts as hereinbefore described, but in addition 15 has the metallic contact members 10 and 11 positioned at the open upper end of the plug and connected electrically respectively with the conducting members 4 and 5. Applicant's device contains a shield 12, preferably of insulating material, such as isinglass or mica, held removably 20 in place by the spring ring 13 positioned in a groove of the body. The ordinary standard plug also includes a shield corresponding to applicant's shield 12, although it is generally placed in a 25 different position, but functions substantially as applicant's shield's function, that is, it prevents molten metal or extremely hot vapor from being projected without the hollow of the body 1 when the fusible or thermal element 8 is destroyed by 30 an excessive flow of current.

A device embodying all of the parts hereinbefore described would constitute an efficient and practicable plug fuse and could be so used, but in order to exhibit applicant's invention, there must be a fuse integrity indicating means in addition. 35

The fuse integrity indicating means of applicant may be of various kinds, but applicant prefers an electric lamp 14, and preferably a distinctive indication lamp, such for instance, as a 40 neon filled lamp, or the glow type, operated by an electrical discharge within the lamp, so that when lighted it will give an arrestive indication even in the presence of white or yellow light as commonly used for illumination. The electric 45 lamp, whatever its form, will generally and preferably have two terminals as 15 and 16. These terminals will be electrically and mechanically connected to metallic prongs as 17 and 18 through a resistor 35 of suitable value and form, such, 50 for instance, as the well known grid leak type. The prongs 17 and 18 will be so formed that they are adapted to cooperate with the metallic contact members 10 and 11, that is, the prongs 17 and 18 will make mechanical and electrical contact 55 with metallic contacts 10 and 11 so that thereby the lamp 14 is in a shunt circuit to the thermal element 8.

Applicant prefers to mount the lamp 14 and the metallic prongs, as 17 and 18, in a hollow disc 60 like structure 19. This structure is made of insulating material and has a substantially flat surface 20 with apertures, as 21, therein so that the light from lamp 14 may shine therethrough. The bottom 22 of the disc 19 is formed of a portion 65 of insulating material cemented or otherwise properly attached to the annulus 19 of the disc and supports, mechanically, in separated position, the metallic prongs, as 17 and 18. The hollow disc 19 is preferably made of such dimension, vertically, as shown in Fig. 5, that it adds a minimum to the total length of the plug, at 70 any rate it does not add an amount sufficient to ordinarily prevent the combined device from being used in those positions where an ordinary standard plug fuse now may be used.

As some strain may be put upon disc 19 in turning the plug into its socket, applicant has provided that the disc 19 shall fit into an oval depression 23 of the hollow body 1. The wall of this oval depression supports the disc 19 so that if strain is placed thereon, the prongs 17 and 18 will not be obliged to stand the strain.

In Fig. 7 applicant has shown a modification, in that the separable indicating portion 24 is made in the form of a tube within which is positioned the lamp 14, and to the metallic ends 25 and 26 to which are connected the terminals 15 and 16 of the lamp. The metallic end pieces 25 and 26 are attached to metallic prongs 17 and 18, just as are shown in Fig. 5, and these prongs function exactly as do the prongs of Fig. 6. In order to prevent strain upon the prongs 17 and 18, in the form as shown by Fig. 7, applicant places the tube 24 in a slight recess of the body 28, corresponding approximately in function to the recess 23 of body 1 of Fig. 1.

In Fig. 8, applicant has shown a further modified form of the device embodying his invention. In this form the disc 19 is let into the tube of the body portion 29 corresponding to the body portion 100 1 of Fig. 2 to such an extent that the top of the disc 19 is flush with the top of the body 29. Applicant illustrates nail spaces 30 and 31 for the insertion of the nail of the finger for the purpose of removing the disc 19.

In Figs. 10 and 11, applicant has illustrated a further modified form of the invention. In this form the body portion is formed in two parts, a lower part 31 and an upper part 32, the combined length being that of the standard plug fuse, 110 the separation being made along the line 33.

In the form as shown by Figs. 10 and 11, the portion 32 corresponding with the disc 19 of Fig. 5 has a cover portion 20 which is held in place by a spring ring 34, thereby enabling one to more 115 readily get to the lamp 14.

From the hereinbefore given description, it will be seen that applicant has provided a combined fuse and fuse integrity indicator formed of two separable parts, one of which corresponds 120 with and is capable of performing all of the functions of the ordinary standard plug fuse, the other of which combined with the first mentioned part serves to indicate the integrity of the thermal element proper, in that when the thermal element 125 proper is destroyed the indicating means will show such facts by the lighting of a lamp.

It is further apparent that all forms of applicant's combined device are such that each has an over-all length not too great to successfully 130 allow the use in those positions in which the ordinary standard fuse is now used, if one bears in mind, that in practically all cases, some slight allowance is made between the end of an ordinary standard plug fuse block and the cover ordinarily 135 used to protect it.

It is further seen that some of applicant's forms, particularly those illustrated by Figs. 8 and 10 are no greater in over-all length than the standard plug fuse and so may be properly used in those 140 situations where an ordinary standard plug fuse is used.

A great advantage of applicant's method of indicating the integrity of the fuse as shown in the 145 drawing and explained in the specification resides in the fact that the indicating means is separable from the thermal element means, so that if the thermal element means is destroyed then upon replacing the destroyed part the indicating means 150

originally and previously used may be combined with the new thermal element portion.

Although I have particularly described several particular physical embodiments of my invention and explained the operation, construction and principle thereof, nevertheless, I desire to have it understood that the forms selected are merely illustrative, but do not exhaust the possible physical embodiments of the idea of means underlying my invention.

What I claim as new and desire to secure by Letters Patent of the United States, is:

1. In a plug fuse, in combination: an insulating hollow body; two terminals on the outside of the body for cooperation with terminals of an electrical circuit to be protected; two combined conducting and mechanical connecting members, each connected electrically to one of the terminals, at least, partially exposed within the body; a thermal element connecting said two conducting members; said conducting members forming contact terminals for cooperation with the contact terminals of a separable thermal element integrity indicator; a thermal element integrity indicator and mechanical connecting means for attaching the integrity indicator to the hollow body cooperating with the said two combined conducting and mechanical connecting members.
2. A combined thermal fuse and fuse integrity indicator consisting of a plug portion and a separable indicating portion; the plug portion comprising an insulating body provided with two terminals for cooperation with terminals of an electrical circuit to be protected, a thermal portion connecting the first mentioned terminals, and two combined metallic electrical and mechanically attaching contacts, one connected to each of the first mentioned terminals; the separable indicating portion including an indicating electric lamp provided with two terminals and two combined metallic electrical and mechanically attaching members, one connected to each of the lamp terminals, for attaching the indicating portion to the plug portion mechanically and electrically connecting the metallic contacts of the plug portion to the metallic members of the indicating portion and a housing for the lamp formed substantially as a hollow disc with observation slits therein.
3. A combined thermal fuse and fuse integrity indicator consisting of a plug portion and a separable indicating portion; the plug portion comprising an insulating body provided with two

terminals for cooperation with terminals of an electrical circuit to be protected; a thermal portion connecting the first mentioned terminals, and two metallic contacts, one connected to each of the first mentioned terminals; the separable indicating portion including a distinctive indication indicating electric lamp provided with two terminals and two metallic members, one connected to each of the lamp terminals, for attaching the indicating portion to the plug portion and electrically connecting the metallic contacts of the plug portion to the metallic members of the indicating portion and substantially a hollow disc formed with observation slits for housing the lamp.

4. A combined fuse and fuse integrity indicator formed of two separable parts; one part having substantially the form and shape of the lower one half terminal end of a standard plug fuse and supporting and containing terminals and a thermal element connecting the terminals and in addition two metallic contacts adjacent the open end; and the other portion corresponding to the upper or manually grasping and manipulating half, separable from the other half, and supporting and containing an indicating lamp having metallic members connected to the terminals thereof for contact with the metallic contacts carried by the other half whereby the whole may be used and positioned for use in the same manner as an ordinary plug fuse but when the thermal element of the fuse becomes destroyed the lamp will light and when renewal of the thermal element is accomplished the original separable indicating lamp portion is used therewith.

5. A fuse integrity indicator formed substantially as a hollow disc with apertures opening in one flat surface; an indicating lamp provided with terminals within the hollow of the disc; and two separated metallic prongs projecting from the substantially flat surface of the disc opposite the surface in which the apertures are formed, one of the metallic prongs being connected to one terminal of the lamp, and the other prong being connected to the other terminal of the lamp, said prongs adapted to contact and make electrical connection with the ends of a fusible element of an electrical circuit thereby placing the lamp in shunt to said fusible element whereby upon the destruction of the fusible element the lamp will be lighted to indicate the disruption of the fusible element.
